(Cl. D58—26)

To all whom it may concern:

Be it known that I, Jacob S. Kwiatkowski, a citizen of the United States and a resident of Toledo, Lucas County, Ohio, have invented a new, original, and ornamental Design for a Combined Bottle Cap and Screw Driver, of which the following is a specification, reference being had to the accompanying drawing, forming a part thereof.

In the drawing:

Figure 2 is an enlarged side elevation of the combined bottle cap and screw driver; and

I claim :

The ornamental design for a combined bottle cap and screw driver, as shown.

JACOB S. KWIATKOWSKI.
